UNITED STATES PATENT OFFICE.

RUSSELL THAYER, OF PHILADELPHIA, PENNSYLVANIA, ASSIGNOR TO THE KITSON HYDROCARBON HEATING AND INCANDESCENT LIGHTING COMPANY, OF PHILADELPHIA, PENNSYLVANIA, A CORPORATION OF WEST VIRGINIA.

OIL-GAS GENERATOR AND BURNER.

SPECIFICATION forming part of Letters Patent No. 750,558, dated January 26, 1904.

Application filed November 21, 1902. Serial No. 132,230. (No model.)

To all whom it may concern:

Be it known that I, RUSSELL THAYER, a citizen of the United States, residing at Philadelphia, in the county of Philadelphia and 5 State of Pennsylvania, have invented new and useful Improvements in Oil-Gas Generators and Burners, of which the following is a specification.

The principal object of the invention is to 10 provide a simple, compact, efficient, and inexpensive apparatus for generating and burning oil-gas, which is adapted and arranged to be received in the fire-box of the ordinary coal range or furnace and supersede coal as a heat- 15 producing medium, the generator being connected with an oil-supply, which may operate by pressure or gravity.

Generically stated, the invention comprises a main burner, a vapor-generator communicating with the main burner and directly exposed to the main-burner flame, and a body overlying the generator and provided with flue-openings and with means for diffusing heat and flames upon the generator.

The invention further comprises a main burner, a vapor-generating coil communicating with the main burner and directly exposed to the main-burner flame, and a deflector overlying the coil and provided with flue-openings and means for partially inclosing the coil.

The invention further comprises a main burner, a vapor-generating coil communicating with the main burner and directly exposed to the main-burner flame, a basin below the coil 35 and burner, and a deflector overlying and supported independently of the coil and burner.

The invention further comprises the burner and vapor-generating apparatus hereinafter described and finally claimed.

The nature, characteristic features, and scope of the invention will be more clearly understood from the following detailed description, taken in connection with the accompanying drawings, forming a part hereof, where- 40 in—

Figure 1 is a central sectional view of a

burner and oil-vaporizing apparatus embodying features of my invention. Fig. 2 is a top plan view of the same. Fig. 3 is a perspective view of the deflector, and Fig. 4 is a sectional view on line 4 4 of Fig. 1.

Referring to the drawings, *a* represents an oil-gas or vapor generator supported in a cast-iron basin *b*, which latter may be of circular or other suitable form adapted to be readily inserted in the fire-box of the ordinary coal range or furnace. The generator *a* is preferably comprised of an inverted spiral coil and is provided at its lower end with an oil-inlet *c* and at its outlet end with an L-shaped vapor-discharge pipe *d*, having an orifice or jet *e*, which constitutes a main burner. The main burner is arranged below and centrally of the coil, and the latter is directly exposed to the flame of said burner. The extension *f* or dead end 55 of the coil constitutes a trap for catching or holding any dirt or sediment which may be in the oil and which is carried over by the gas, and by the provision of a screw-threaded plug *g* the accumulations of dirt and sediment may 60 be removed from time to time, and the burner 65 thus kept clean.

The oil-gas or vapor-generating coil *a* is covered by an overlying body *h*, of refractory material, supported in any suitable manner, 75 as by the vertical supports or legs *i*, which rest upon the basin *b* and permit free access of air to the burner. The body *h* is provided on its under side and concentrically of the coil with a convex portion or baffle *j*, which is di- 80 rected axially of the coil and constitutes a deflector or spreader for diffusing the heat and flames upon the several helices or convolutions of the coil.

k represents flue-openings in the body *h* 85 for the emission of flames and products of combustion, and *l* is a downwardly-extending seg- 90 mental flange which deflects heat upon the discharge-pipe *d* and also partly incloses the coil.

The operation of the apparatus is as follows: Combustible matter—as oil, paper, or kin-

dling—is placed in the basin *b* and ignited, and oil is supplied to the coil either by gravity or under pressure. The oil escapes at the jet or burner *e* and is ignited by the fire in the basin. In a very short time the coil is sufficiently heated by burning oil to vaporize further supplies of oil, and the vapor escapes and burns at the orifice *e*. The flame is deflected by the baffle *j*, and a portion escapes around the casting *h l* and between the supports of the same and in so doing heats to redness the upper portion of the coil. A smokeless flame also issues from the apertures *k* in the overlying member or body *h*, and the latter becomes very hot and refracts heat back upon the coil. By this means the oil is perfectly converted into a highly-combustible gas, and its entire heat may be utilized in the range or heater for cooking or heating purposes.

It will be observed that the process of vaporization is a gradual one—that is to say, the oil is gradually heated up to a very high temperature before being vaporized and when vaporized is instantly discharged and consumed. In other words, owing to the peculiar construction of the apparatus the lower helices of the coil are not as hot as the upper helix, the fact being that when the burner is first started the lower portion of the coil is black. As soon, however, as the apparatus begins to generate vapor the lower portion of the coil takes on a dull red color, while the upper helix becomes a bright red.

It will be apparent that on large ranges and the like a battery of two or more of these oil-gas generators and burners may be placed in juxtaposition on the grate-bars and connected together for simultaneous operation, thereby affording a relatively increased heating capacity.

It will be obvious to those skilled in the art to which the invention relates that modifications may be made in details without departing from the spirit and scope of the same. Hence I do not limit myself to the precise construction and arrangement of parts hereinbefore described, and illustrated in the accompanying drawings; but,

Having described the nature and objects of the invention, what is claimed as new, and desired to be secured by Letters Patent, is—

1. The combination of a main burner, a vapor-generator consisting of a helical coil which communicates with the main burner and whereof the helices are exposed to the main-burner flame, and a refractory body overlying and supported independently of the generator and burner and provided with a depending convex portion which projects

partly within the axial plane of the coil and 60 constitutes a spreader for the main-burner flame, and with openings at the base of said convex portion for the emission of flames and products of combustion, and with an overhang or flange, which constitutes a baffle for the 65 discharge end of the coil, substantially as described.

2. The combination of a vapor-generator consisting of an inverted spiral coil provided at its lower end with an oil-inlet and having 70 its other end extending downwardly and transversely of the coil and served centrally thereof with a vapor-discharge outlet, a basin below the coil, and a detachable refractory body overlying the coil and having a depending 75 convex portion which projects partly within the axial plane of the coil to constitute a spreader for the flame, and having openings at the base of said convex portion for the emission of flames and products of combus- 80

3. The combination of a vapor-generator consisting of an inverted spiral coil provided at one end with an oil-inlet and having its other end terminating in an L-shaped portion 85 which extends below the coil and is provided axially thereof with a vapor-discharge outlet, a basin below the coil, and a detachable refractory body overlying the coil and having legs or supports which rest upon the bottom 90 of the basin, said body having a downwardly-directed convex portion or spreader projecting partly within the axial plane of the coil, and having an overhang or flange, which constitutes a baffle for said L-shaped portion, sub- 95 stantially as described.

4. The combination of a vapor-generator consisting of an inverted spiral coil provided at one end with an oil-inlet and having its other end terminating in an L-shaped portion 100 which extends below the coil and is provided axially thereof with a vapor-discharge outlet, a basin below the coil, a detachable refractory body overlying the coil and having legs or supports which rest upon the bottom of the 105 basin, said body having a downwardly-directed convex portion or spreader projecting partly within the axial plane of the coil, and a depending segmental flange which serves to deflect heat upon said L-shaped or discharge 110 portion of the coil, substantially as described.

In testimony whereof I have hereunto signed my name in the presence of two subscribing witnesses.

RUSSELL THAYER.
